Primary Examiner — Karen S Acker(74) *Attorney, Agent, or Firm* — Brinks Gilson & Lione(57) **CLAIM**

We claim the ornamental design for a molded anti-fatigue mat, as shown and described.

DESCRIPTION

FIG. 1 is a top plan view of a molded anti-fatigue mat. FIG. 2 is a side elevation view taken from the top of FIG. 1, the opposite side being a mirror image.

FIG. 3 is a side elevation view taken from the right side of FIG. 1, the opposite side being a mirror image.

FIG. 4 is a sectional view taken along line 4-4 of FIG. 1.

FIG. 5 is an enlargement of that portion of FIG. 4 within circle 5.

FIG. 6 is a bottom plan view of the molded anti-fatigue mat of FIG. 1; and,

FIG. 7 is an enlarged sectional view taken along line 7-7 of FIG. 6.
